UNITED STATES PATENT OFFICE.

WILLIAM M. SCHOLL, OF CHICAGO, ILLINOIS.

FOOT-CORRECTIVE APPLIANCE.

Application filed April 2, 1925. Serial No. 20,051.

The invention relates to foot corrective appliances.

One of the objects of the invention is to provide a yielding, resilient means to support the outer longitudinal arch of the foot by raising and supporting the front end of the os calcis, the cuboid and the posterior end of the fifth metatarsal bones of the foot near where they articulate, to induce outward tilting of the foot in weak inwardly rolled feet and to relieve the outer plantar muscles of fatigue and undue stress.

Another object is to provide a yielding heel-cushion to receive the os calcis and its covering and which is resilient so as to serve as a shock absorber where the shock is produced by impact of the heel of the foot of the walker with an unyielding roadway.

A further object is to make the upper surfaces of the heel-receiving cushion inclined inwardly at an angle to a horizontal plane to encourage the foot to tilt outwardly about the tibia so as to restore and to maintain it in its natural position.

The device is intended to correct the tendency to walk on the outer longitudinal edge of the foot in which the inner plantar surfaces, or soles of the feet are raised, as when the legs of the afflicted person are outwardly bowed.

Other objects, advantages and benefits will become apparent to persons skilled in the art, from a consideration of the following description, when taken in conjunction with the drawings, wherein:

Figure 1 is a plan view of the device.

Figure 2 is a longitudinal section taken on line II—II of Figure 1.

Figure 3 is a transverse section taken on line III—III of Figure 1.

Figure 4 is a rear view of the device in elevation.

As shown on the drawings:

The preferred form of the device is shown in plan view in Figure 1, in which the reference numeral 5 indicates a resilient triangular plate, made preferably of soft rubber. It is triangular in form having a base line 6 and a line 7 describing the hypotenuse and a rear curved leg 8. The device shown is for insertion in a shoe near the heel thereof upon the right foot on which the shoe is to be worn. The plate 5 tapers fore and aft from the rear portion 9 to the front portion 10, just in the rear of the vertical protuberance 11, and it also tapers from the base line 6 to the hypotenuse 7 as more clearly shown in Figures 2 and 3.

To hold the device 5 in proper position in the shoe I prefer to use a flexible plate 12, preferably of leather, to which the plate 5 is cemented or otherwise secured. The plate 12 is skived across its front edge as at 13. The plate 12 is somewhat larger in outline than the plate 5 leaving a margin 14 between the two and the outside of the rear portion of the shoe heel. I prefer to perforate the plates 5 and 12 with registering spaced perforations 15, the axes of which are preferably in vertical planes and thereby leaving an imperforate margin 16 around the group of perforations. The object of this is to render the enclosed perforated zone of the plate 5 less resistant to pressure so that the heel portion of the foot will make a depression more or less into the yielding body of the plate 5 and the outer surface of the heel will rest on the imperforate margin which will bear the weight of the wearer imposed thereon. Pressure is not imposed upon the central part of the os calcis of the foot but around the more rigid edge thereof. The plate 5 is tapered as described for the purpose of causing the right foot, in the present instance, to be tilted outwardly or the angle inwardly to prevent the wearer from walking upon the outer longitudinal edge of the foot and shoe.

The yielding protuberance 11 supports the posterior portion of the fifth metatarsal and tends to support the front end of the os calcis and the intervening cuboid bone of the foot and thus it restores and maintains the outer longitudinal arch-forming bones in their proper positions and relieves the outer plantar muscles of undue strain until the strength of the foot has been recuperated and the parts are able to maintain their natural form and position unassisted. The perforations 15 also serve as means for ventilating through the inner zone of the soft rubber plate, and furthermore, they contain air which serves, more or less, to produce a cushioning effect upon the plantar surface of the heel. The plate 5 serves as a shock absorber to relieve the foot of the sudden and harsh impact of the foot when the walker strikes his heel upon an unyielding roadway surface. The extent to which the plate 5 may be longitudinally and laterally tapered will depend somewhat upon the ease in hand and this may be varied in

order to meet the deformed conditions as they may be found.

The protuberance 11 is located at a point where the base line 6 and the line of the hypotenuse 7 meet and at the front end of the device which is about the proper location for performing the functions described.

It is manifest that the part 5 may be used alone and properly secured in the heel of the shoe, but it is best to use the leather plate 12 and secure the part 5 thereto as this prevents the shifting of the part 5 in the shoe and produces, to some extent, the elevation of the heel which is one object of the device, as means for lifting the outer longitudinal arch.

Having described my invention, what I claim as new and desire to secure by Letters Patent, is:—

- 20 1. A cushion device for insertion within a shoe, comprising a resilient plate generally triangular in plan outline with its base line substantially parallel with the outer edge of the heel part of the shoe and its rear outline rounded to conform generally to the inner rear part of the shoe heel, said plate being tapered transversely and inwardly from the aforesaid base line toward the
- 25

hypotenuse of the aforesaid outline, said plate having its central zone perforated at 30 frequent intervals by spaced openings leaving an imperforate marginal edge and having a protuberance extending vertically near the intersection of said base and said hypotenuse to support the bones of the outer longitudinal arch of the foot.

2. A cushion device for insertion within a shoe comprising a resilient plate of soft rubber, generally triangular in plan outline, with its base line substantially parallel with 40 the outer edge of the heel part of the shoe and its rear outline rounded to conform generally to the inner rear part of the shoe heel, said plate being tapered transversely and inwardly from the aforesaid base line 45 toward the hypotenuse of the triangle and forwardly from said rear curved end; an underlying plate of relatively rigid material to which the resilient plate is attached, both plates having spaced apertures extending vertically therethru leaving an imperforate margin near the base and rounded rear outline of the superposed resilient plate.

In testimony whereof I have hereunto subscribed my name.

WILLIAM M. SCHOLL.
